UNITED STATES PATENT OFFICE.

ORSON W. BRENIZER, OF PHILADELPHIA, PENNSYLVANIA, ASSIGNOR OF ONE-HALF
TO ALEXANDER H. BOYD, OF PHILADELPHIA, PENNSYLVANIA.

HAIR CURLER.

Application filed February 1, 1922. Serial No. 533,232.

To all whom it may concern:

Be it known that I, ORSON W. BRENIZER, a citizen of the United States, residing at Philadelphia, in the county of Philadelphia and State of Pennsylvania, have invented 5 certain new and useful Improvements in Hair Curlers, of which the following is a specification.

This invention relates to improvements in 10 hair curlers of the type formed of a single piece or strip of resilient metal and comprising two arms connected at one end thereof and having a backwardly and inwardly turned hook on the free end of one arm 15 adapted to engage a part of the free end of the other arm to hold the free ends of the arms detachably engaged with each other when hair is placed between them and at least one of the arms is bowed outwardly by the 20 hair as the free ends of the arms are brought together, and in which the free end portion of one arm is adapted to be passed laterally under the free end of the hook of the other arm in connecting and disconnecting the free 25 ends of the arms.

In curlers of this type the free end of one arm is not only passed laterally under the free end of the hook of the other arm but thereafter it is permitted to spring outwardly for engagement with other parts of the hook, and it is desirable that the space 30 between the free end of the hook and the arm on which it is formed shall be as small as possible to prevent accidental disengagement of the free ends of the arms when the curler is in service; and much difficulty has 35 been experienced in springing the metal of the curler to bring the free ends of the arms toward each other and to move them laterally relatively to each other in connecting 40 and disconnecting them due to their close relationship. One of the objects of my invention is to overcome this difficulty.

Curlers of the aforesaid type constructed 45 with a notch in the hook to receive a neck connecting a head to the main body of the other arm to prevent accidental separation of the detachably connected ends of the arms when the curler is in service have been found 50 in practice to be defective and have failed to perform their function of preventing the withdrawal of the head from the hook by the bowing or longitudinal displacement of one of the arms. Another object of my invention is to overcome this defect and to

provide a novel curler in which the parts are constructed and related to positively prevent the said withdrawal of the head from the hook when the curler is in service.

The invention consists in the novel construction, combination and arrangement of parts whereby the aforesaid difficulty and defect are overcome as will be hereinafter described and claimed.

In the accompanying drawings, illustrating the invention,

Figure 1 is a top view of a hair curler embodying my invention, the same being shown in the closed position.

Figure 2 is a side view thereof.

Figure 3 is a side view of the curler in the open position.

Figure 4 is a side view of the curler in the closed position in service with hair wrapped around one of its arms.

Figure 5 is a transverse section through the curler on line 5—5 of Fig. 2, showing details of the locking hook and the arms engaged therewith.

Figure 6 is a view of the free end portion 80 of one of the arms.

Referring to the drawings, the curler comprises two arms 2 and 3 connected at one end thereof by a small bowed or loop portion 4, the whole being formed of a single piece or 85 strip of resilient metal.

In the normal condition of the curler the arms 2 and 3 diverge from their connected ends to form an open space between them, as shown in Fig. 3, for the reception of hair 90 to be wrapped around the arm 2.

The free end portion of the arm 3 has a backwardly and inwardly turned hook 6 formed thereon and the free end portion of the hook has a notch 7 formed therein which 95 opens toward the body of the arm 3.

The free end portion of the arm 2 is of sinuous form having an inwardly bowed portion 8 connected to the main body of the arm 2 by an outwardly bowed portion 9. The 100 free end of the inwardly bowed portion 8 has a head 10 formed thereon connected to the main body of the arm 2 by a narrow neck 11 which forms that part of the inwardly bowed portion 8 which is nearest to 105 the arm 3 and which is adapted to be passed under the free end of the hook 6 and into and from the notch 7 in connecting and disconnecting the normally free ends of the 110 arms 2 and 3.

The notch 7 is provided with substantially parallel, opposing side walls, between which the neck 11 is received, and the head 10 is wider than the space between the side walls 5 of the notch 7, and the side walls of the notch 7 cross the neck substantially at right angles thereto, so that when the neck 11 is within the notch 7, as shown in Figs. 1, 2, 10 and 5, the side walls of the notch and the projecting sides of the head 10 will engage each other and effectually prevent the accidental disengagement of the free end portion of the arm 2 from the hook by any attempt to displace the free end of one arm 15 relatively to the other in a longitudinal direction.

The free end of the hook 6 extends to a position close to the body of the arm 3 leaving only sufficient space between them for the 20 passage of the neck portion 11 laterally into and from a position opposite to the notch 7, and, when the neck 11 is passed into and from the notch 7, the outwardly bowed portion 9 of the arm 2 always presents an edge portion 25 of the arm 2 spaced from the opposite edge portion of the arm 3 to be engaged by the thumb or finger of the user of the curler and permit the neck 11 to be easily and quickly passed into and from the notch 7 30 and the space between the free end of the hook 6 and the body of the arm 3. In other words, opposing pressures of the thumb and finger of the user of the curler against the hooked free end portion of the arm 3 and 35 the outwardly bowed portion 9 of the arm 2 and against the edges thereof will permit the head 10 to be easily and quickly inserted into or removed from the hook 6.

The hair to be curled is wrapped around 40 the arm 2 in the usual manner when the curler is open, as shown in Fig. 3, and the normally free ends of the arms 2 and 3 are then connected as previously described, as shown in Fig. 4; and, when the arms 2 and 3

are thus connected, it is impossible for them 45 to be accidentally disconnected while the curler is in service, irrespective of the quantity of hair which is clamped between the two arms 2 and 3.

I claim as my invention:

1. A hair curler comprising two arms connected at one end thereof, the free end portion of one of the arms forming a backwardly and inwardly turned hook, the free end portion of the other arm having an inwardly bowed portion connected to the main body portion of the arm by an outwardly bowed portion, said inwardly bowed portion being adapted to be passed under the free end of said hook and to engage the opposite arm and maintain said outwardly bowed portion in spaced relation thereto in connecting and disconnecting the free end portions of the arms, and said hook and said inwardly bowed portion having co-operating 60 parts crossing each other and preventing accidental separation thereof when they are engaged with each other.

2. A hair curler comprising two arms connected at one end thereof, the free end portion of one of the arms forming a backwardly and inwardly turned hook having a notch therein, the free end portion of the other arm forming a head wider than said notch and a neck connecting the head to 70 the main body of the arm and being adapted to enter said notch, said neck being adapted to be passed under the free end of said hook and into and from said notch in connecting and disconnecting the free end portions of 75 the arms, and said notch having substantially parallel, opposing walls adapted to engage said head and prevent it from being accidentally withdrawn from the hook by the outward bowing of one of said arms. 80

In testimony whereof I affix my signature hereto.

ORSON W. BRENIZER.
